Attorney

UNITED STATES PATENT OFFICE.

CHARLOTTE M. PUTNAM, OF FALLS CITY, NEBRASKA.

REVERSIBLE HAND-COVERING.

1,351,685.

Specification of Letters Patent. Patented Aug. 31, 1920.

Application filed October 1, 1917. Serial No. 194,186.

To all whom it may concern:

Be it known that I, CHARLOTTE M. PUTNAM, a citizen of the United States, residing at Falls City, in the county of Richardson 5 and State of Nebraska, have invented certain new and useful Improvements in Reversible Hand-Coverings, of which the following is a specification.

This invention relates to hand coverings 10 and it is the principal object of the invention to simplify and reduce the cost of manufacture of constructions of reversible mittens of the type disclosed in my prior Patent No. 1,287,694 granted August 21, 15 1917, and provide novel details in the construction and arrangement of parts with a view to higher efficiency generally.

The improvements in the details and arrangement of parts will be apparent from 20 an inspection of the accompanying drawings, in connection with the specific description hereinafter contained, and wherein the preferred embodiment of the invention is disclosed for the purpose of imparting a full 25 understanding of the present improvements.

In the drawings:

Figure 1, is a perspective of the mitten; Fig. 2, is a plan of the blank, and,

Fig. 3, is a plan of one of the thumb 30 blanks.

Having more particular reference to the drawings, the mitten includes a blank designated by the numeral 1, the same being so formed as to permit folding thereof along 35 the longitudinal line 2 to provide a covering for the hand. A tongue 3 is cut from the lower portion of the blank 1 at a point adjacent the longitudinal line 2 and as will be understood, forms a suitable thumb part.

40 A second tongue 4 is formed by slitting the material of the blank 1 at a point adjacent one side edge thereof and serves as a second thumb part.

It is to be noted that the side edge carrying the tongue 4 is formed or cut as at 5 in order that the same will project slightly beyond the opposite side edge providing a flap-like extension which, when the coinciding parts of the blank 1 are folded together, 50 may be turned over said opposite edge and the adjacent edges of the blank joined by stitching.

Those portions of the blank intermediate

the tongues 3 and 4 obviously serve as an efficient wrist covering for the wearer, it 55 being understood that the marginal edges of the same are also united by stitching.

Thumb blanks 6 of the type illustrated in Fig. 3 are provided and one is stitched or otherwise secured to the edges of the thumb part 3 and along the edges of the slits in the main blank 1 defining the part 3 thereby forming a pocket for the reception of the thumb of the wearer. The other thumb blank 6 is stitched to the thumb part 4 and along one side edge to the edge of the slit in the blank 1 defining the part 4. A portion of the opposite side edge of said other blank 6 is secured along the side edge of the blank 1 opposite the thumb part 4 thereby 70 forming a second pocket for the reception of the thumb when the glove is reversed and worn upon the other hand of the wearer.

Owing to the manner of inclosing one edge of the blank in the flap of the other 75 edge the joint between the meeting edges of the blank is materially reinforced. Further, due to the positioning of the thumb parts 3 and 4, the glove may be readily reversed, that is, used upon either the right 80 or left hand of a person. Joining of the coinciding parts of the blank by stitching is also facilitated, due to the positioning or arrangement of the thumb parts 3 and 4, it being noted that but a single row of stitching is required.

Manifestly, the construction shown is capable of considerable modification and such modification as is within the scope of my claim, I consider within the spirit of my invention.

I claim:

In a reversible mitten, a one piece body 95 folded longitudinally to provide a front and back and having a pair of slits adjacent the line of fold providing a tongue and another slit adjacent one side edge providing a second tongue, a thumb blank secured to the first tongue and edges of the pair of slits, and a second thumb blank secured to the 100 second tongue and to the edge of said other slit and directly to the side edge of the body opposite the second tongue.

In testimony whereof, I affix my signature hereto.

CHARLOTTE M. PUTMAN.
